INDIRECTLY HEATED CATHODE

Horst Rothe, Berlin, Germany, assignor to Tele-funken Gesellschaft für Drahtlose Telegraphie m. b. H., Berlin, Germany, a corporation of Germany

Application August 4, 1932, Serial No. 627,428
In Germany August 7, 1931

3 Claims. (Cl. 250—27.5)

This invention relates to thermionic tubes, and more particularly to indirectly heated cathodes for use in such tubes.

As known in the prior art, and in present-day form of constructions, indirectly heated cathodes are provided with rod-shaped cores of insulation material, such as alumina, with slender bores into which the heater, for instance, a wire or a spiral or loop of tungsten is threaded. Because of the high thermal capacity and the low heat conducting power of the insulation materials the aggregate starting time in heating such cathodes amounts to about 1 minute. It has been previously suggested to reduce this heating time by having some parts of the insulation body ground away so that the heater element may be supported by the insulation material only locally or in some places, while being free or exposed otherwise so that it is enabled to radiate the heat freely and directly to the surrounding cathode sleeve or shell consisting, for instance, of a nickel tube fitted over the insulating core. However, the work of grinding away some of the insulation is attended with serious difficulties.

Now, in order that the advantage offered by the fact that at least part of the heater body is exposed, may be combined with ease of manufacture, the insulation body or core is constructed as illustrated in Figs. 1 and 1A in accordance with one form of the invention. Figs. 2 and 2A disclose a second modification in accordance with this invention. In the modification shown in Figs. 1 and 1A the insulation body or core consists essentially of a slender or thin central part *a* of circular cross-sectional form, and in the modification shown in Figs. 2 and 2A the central core *a'* is flat or shaped in the form of a rectangle. In each modification the insulation body or core is provided with thickened portions *b* at both ends and also at one or more intermediate parts thereof, the diameter thereof corresponding exactly to the inner diameter of the nickel tubelet *c* fitted thereover. The raised or heavier portions are provided with radially extending slots at two or more opposite points in a longitudinal direction of the insulation body and may be formed by pressure, said slots being just large enough to receive the heater wire provided for heating the cathode. Since these insulation

bodies have no internal bores they can be readily formed by pressing mechanically. The heater wire may be hairpin shaped, for instance, and is mechanically supported in the slots of the thickened portions. The means for mechanically supporting the heater wire may be improved by closing the slots with a highly refractory cement hardened upon the heating of the filament during exhaustion. The number and the cross-section of the thickened portions of the insulation body must be so chosen that the heater wire is easily held or supported in its position symmetrically in reference to the outer cathode tubelet and that no electrically conducting paths with the same will be produced.

What is claimed is:

1. An indirectly heated cathode comprising an electron emitting tubular member, a core of insulating material centrally arranged within and spaced from the inner wall of the tubular member, a plurality of circular discs of insulating material interposed between said insulating core and said inner wall, each disc being provided with radial slots which extend from the surface of the central core to the disc periphery and which are in alignment with corresponding slots of the remaining discs, and a filamentary heater wire threaded through such slots.

2. An indirectly heated cathode comprising a tubular electron emitting member, an insulating core coaxially arranged within the tubular member and provided at each end with an enlarged circular insulating disc adapted to fit snugly within the tubular member, said circular discs having diametrically opposite radial notches which extend all the way to the disc peripheries, the notches of one disc being longitudinally aligned with the notches of the other, and a hairpin heater wire threaded through said notches.

3. An insulating core for electron discharge cathode heaters comprising an insulating core provided along its length in spaced relation with enlarged circular insulating discs, said circular discs having radial notches which extend all the way to the disc peripheries, and the notches of one disc being longitudinally aligned with the notches of the other.

HORST ROTHE.
